The ornamental design for the trigger for aerosol container discharging apparatus, as shown and described.

DESCRIPTION

FIG. 1 is a reduced perspective view of the trigger for aerosol container discharging apparatus shown in the condition of use;

FIG. 2 is a perspective view of the trigger for aerosol container discharging apparatus;

FIG. 3 is a right side elevational view of the trigger for aerosol container discharging apparatus;

FIG. 4 is a left side elevational view of the trigger for aerosol container discharging apparatus;

FIG. 5 is a front end view of the trigger for aerosol container discharging apparatus;

FIG. 6 is a rear end view of the trigger for aerosol container discharging apparatus;

FIG. 7 is a top plan view of the trigger for aerosol container discharging apparatus; and,

FIG. 8 is a bottom plan view of the trigger for aerosol container discharging apparatus.

All broken lines in the drawing views are included for the purpose of illustrating portions of the trigger for aerosol container discharging apparatus that form no part of the claimed design.
